KEY RING CONSTRUCTION

William J. Morse, Attleboro, Mass., assignor to
Morse Andrews Co., a corporation of Massa-
chusetts

Application November 8, 1944, Serial No. 562,495

6 Claims. (Cl. 70—459)

1

The present invention pertains to the jewelry art, and has particular reference to a novel construction for a key ring.

The principal object of the invention is to provide a key ring construction which lends itself to ornamentation.

Another object of the invention is to provide a key ring construction which includes a key passageway for inserting and removing keys, the key passageway being normally positively sealed to prevent accidental release of a key or keys.

A further object is to provide a key ring construction made of a small number of readily manufactured and assembled parts.

With the above and other objects and advantageous features in view, the invention consists of a novel arrangement of parts more fully disclosed in the detailed description following, in conjunction with the accompanying drawings, and more specifically defined in the claims appended thereto.

In the drawings,

Fig. 1 is a plan view of a key ring embodying the novel construction, as it appears when in use;

Fig. 2 is a rear view thereof, the parts being in position for insertion of a key or keys;

Fig. 3 is a view similar to Fig. 2, the cover being shown in section to disclose the arrangement of the operating parts;

Fig. 4 is a perspective view of the cover;

Fig. 5 is a perspective view of the retainer block;

Fig. 6 is a view similar to Fig. 3, illustrating a modified construction; and

Fig. 7 is a perspective view of the modified retainer block therefor.

It has been found desirable to provide a key ring which is adapted for ornamentation and which positively retains the keys in place against accidental loss or removal. To this end, I have devised a key ring construction which utilizes a cover which may be suitably ornamented, and within which the key passageway is normally positioned, thus precluding unintentional release of a key. The parts are specifically designed to be of rugged construction and few in number, in order to permit quantity production and to expedite manufacture and assembly.

Referring to the drawings, the novel key ring 10 includes a cover 11 which is preferably made of sheet metal and is of hollow construction, to provide a housing for the operating parts. Seated within the cover is a frame 12, preferably made of wire and shaped as shown in Fig. 3, to form

2

a narrow loop end 13 which is adapted to slidably fit within the correspondingly shaped opening 14 at the upper end of the cover, one side of the frame then extending laterally to provide a vertical side 15, a horizontal key bar 16, and a vertical side 17, and the other side similarly spreading laterally to provide a short downwardly extending side 18 in alignment with and spaced from the upper end of the vertical side 17 to provide a key passageway 19.

The vertical sides of the lower portion of the frame seat in sliding engagement with the inner walls 20, 21 of the cover, whereby the cover guides both the upper loop end and the lower portion of the frame. A cross bar 22 is soldered or secured in any other suitable manner between the wire sides forming the loop end of the frame, see Fig. 3, to serve as an abutment for one end of a tension coil spring 23, the other end of the coil spring being seated in a recess 24 in the upper surface of a retaining block 25. As illustrated in Fig. 5 the retainer block has a horizontal groove 26 extending across one face 27; after the parts are assembled as disclosed in Fig. 3 the cover is struck or swaged as indicated by the reference numeral 28 to seat into the groove 26, see Fig. 2, thus locking the key ring parts in assembled relation.

The upper portion of the frame loop end forms 30 a link 29 for attaching a chain or the like, and the key passageway 19 is normally positioned within the cover. When the upper end of the frame is pressed down, the cover being held in the hand, the frame moves downwardly to expose 35 the key passageway as disclosed in Fig. 2, thus permitting keys to be inserted or removed. The keys normally seat on the horizontal key bar, and the upward movement of the frame resulting from the pressure of the coil spring conceals 40 the key passageway within the cover, thus holding the keys securely without danger of accidental loss.

The novel construction may be changed to accord with different key ring designs. Thus, it 45 is often desired to have two separate key ring sections in order to keep special keys separate. To this end I have modified the construction by shaping the frame as indicated by the reference numeral 29a to provide an end loop 30 having 50 two vertical sides 31 which are turned at their lower ends to form U-shaped terminals 32, 33, the outer sides of the terminals providing key receiving tongues 34, 35. The retainer block 36, see Fig. 7, has two recesses 37 adapted to slid- 55 ingly receive the vertical sides 31, and a central

shallow bore or seat 38 to receive the lower end of a tension coil spring 39, the upper end of the spring seating against a cross bar 40 which is secured between the sides 31 below the end loop 30. The cover 41 is provided with an upper opening 42 to slidably receive the end loop 30, and is swaged or struck to seat into the horizontal groove 43, provided in the side 44 of the retainer block as illustrated, the upper ends of the tongues 34, 35 thus being normally housed within the cover until the frame is moved downwardly against the tension of the spring 39. The modified construction thus provides a double key ring construction.

Although I have described illustrative specific constructions which have a small number of readily manufactured and assembled parts, it is obvious that the size, shape, and arrangement of the parts may be varied to provide different key ring designs, and that the invention may be applied by suitable modification understood in the art to other jewelry constructions, such as clasps, buckles, attaching link devices and the like, without departing from the spirit and the scope of the invention as defined in the appended claims.

I claim:

1. In a key ring, a cover of hollow formation, a wire frame slidably seated in said cover and having an upper loop portion extending through the upper end of the cover and a lower key retainer section extending through the lower end of the cover, one side of said key retainer section having a key passageway normally positioned within the cover, a cross bar secured between the sides of the upper loop portion, a retainer block positioned in the key retainer section and secured to the cover and positioned to normally seal the key passageway, and a spring device extending between the cross bar and the retainer block, whereby downward movement of the wire frame against the tension of the spring device exposes the key passageway below the cover.

2. In combination, a cover of hollow formation, a frame slidably seated in said cover and having a lower open portion extending below the cover, one side of said open portion having a key passageway therethrough which is normally positioned within the cover, a retainer element secured to the cover and positioned in said open portion to normally seal the key passageway, and a spring means in said cover between said frame and said retainer element, whereby downward movement of said frame within the cover against the tension of the spring means exposes the passageway below the cover.

3. In combination, a cover of hollow formation, a frame slidably seated in said cover and having an upper loop portion extending from the upper portion of the cover and a lower open loop portion extending from the lower portion of the cover, one side of the open loop portion having a key passageway therethrough which is normally positioned within the cover, a retainer element secured to the cover and positioned within the open loop portion and normally sealing the key passageway, an abutment on said upper loop por-

tion, and spring means in said cover between said abutment and said retainer element, whereby movement of said frame within said cover against the tension of said spring means exposes said key passageway below said cover.

4. In combination, a cover of hollow formation, a frame seated for sliding movement therein and having two lower U-shaped portions extending below the cover with their free ends extending upwardly and normally housed within the lower portion of the cover, a retainer element secured to said cover adjacent the lower end thereof and positioned to seal the free ends of the U-shaped portions, and a spring device within said cover engaging said retainer element and the upper portion of the frame, whereby movement of the frame against the tension of the spring device exposes the free ends of the U-shaped portions below the cover.

5. In combination, a cover of hollow formation, a frame seated for sliding movement therein and having two lower U-shaped portions extending below the cover with their free ends extending upwardly and normally housed within the lower portion of the cover, said frame also having an upper loop portion extending from the upper portion of the cover and provided with a spring abutment, a retainer block secured within said cover adjacent the lower end thereof and positioned to seal the free ends of the U-shaped portions, and a spring device positioned between said abutment and said retainer block, whereby movement of the frame against the tension of the spring device exposes the free ends of the U-shaped portions below the cover.

6. In a key ring, a cover of hollow formation, a wire frame slidably seated in said cover and having an upper loop portion extending through the upper end of the cover and a lower key retainer section extending through the lower end of the cover, one side of said key retainer section having an upwardly extending key receiving tongue normally extending into the cover, an abutment positioned between the sides of the upper loop portion, a retainer block in the key retainer section and secured to the cover and normally sealing the upper edge of the key receiving tongue, and a spring device extending between the abutment and the retainer block, whereby downward movement of the wire frame within the cover against the tension of the spring device exposes the key receiving tongue below the cover.
